UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

METHOD OF AND APPARATUS FOR FORMING RECEPTACLES.

Application filed October 20, 1920. Serial No. 418,973.

To all whom it may concern:

Be it known that I, CESARE BARBIERI, a citizen of the United States, residing at New York, in the county of New York and State of New York, have invented certain new and useful Improvements in Methods of and Apparatus for Forming Receptacles, of which the following is a specification, reference being had therein to the accompanying drawing.

My invention relates to a method of and apparatus for forming tapered or conical drinking cups and receptacles from paper or like substances.

Some of the methods and machinery now in use for making this type of receptacle form the blank into its final shape or conical form during the formative stages previous to the completion of the receptacle. This involves complicated mechanism for so doing, varying according to the original shape of the blank from which the cup is formed, and generally requires a large blank to provide a wide space for the adhesive in order to obtain an instantaneous and substantial sealing of the cup before the natural setting of the adhesive takes place.

Heretofore it has been the practice to form the cups or receptacles from paper previously prepared with paraffin or wax, using the paraffin as the adhesive agent. Since the adhesive properties of the paraffin is limited and easily effected by temperature, a larger blank was required in order to provide sufficient paper to fold several times about the blank.

Attempts have been made to form a conical paper cup from plain paper and to paraffin or wax it after formation, but the process has been found slow and expensive.

In the invention herein set forth, I have obviated among others the objections above pointed out in providing a method which involves several simple steps by which the original blank is folded, sealed, and waterproofed, each step contemplating a working of the blank while flat.

The invention herein disclosed contemplates an economical use of the material from which the cup is formed as well as a saving of time during the formation of the cups, both of which are important factors

in this class of invention in the commercial field.

The method contemplates the several steps by which a blank is cut, or previously cut blank is formed into the finished article and broadly consists in obtaining a blank substantially in the form of a development of a cone, applying an adhesive to one edge thereof and folding substantially equal portions of the blank one upon the other, bending the folded blank to form a sealing strip, applying an adhesive to the sealing strip, sealing the strip upon the blank, and applying a waterproofing agency to the formed blank. Thus far the cup has been completely formed in collapsed form and may be packed for shipment after drying or it may be opened to conical form to permit the drying or partial drying of the waterproofing agency. The cup is thus completed and may be packed in its conical form by nesting, or may be folded flat for economy of space and ease of packing.

The apparatus by which the several steps are accomplished comprises broadly several instrumentalities, operating automatically and in a predetermined order and time, which receive a cut blank, or by preference cut a blank from a supply of paper or like material, and feed the blank through the machine in a substantially horizontal plane. During the progression of the blank through the machine, the several steps herein referred to are accomplished, the blank remaining flat during the while. After the completion or final forming of the blank, it may be delivered from the machine while flat or presented to a mechanism which operates to open the blank to a tapered or conical form, and delivers it for removal from the machine.

Figure 1 is a side elevation of the apparatus;

Fig. 2 is a plan view thereof;

Fig. 3 is a longitudinal section through the machine;

Fig. 4 is a plan view with certain parts removed;

Fig. 5 is an end view showing the mechanism for opening the completed blank into final form;

with to finally shape the completed blank;

Fig. 7 is a detail view showing the plate or carrier and the position the blank assumes when delivered thereto;

Fig. 8 illustrates the position the blank assumes at the time of delivery to the bending and folding element for the first folding;

Fig. 9 shows the first bending of the blank by the bending and folding element;

Fig. 10 is an end view of the parts shown in Fig. 7, looking toward the delivery end of the machine;

Fig. 11 is a sectional view illustrating the parts shown in Fig. 8;

Fig. 12 is a sectional view illustrating the parts shown in Fig. 9;

Fig. 13 illustrates the blank emerging from the bending and folding element and the bending of the sealing strip;

Fig. 14 illustrates a further forward movement of the blank and the sealing of the sealing strip;

Fig. 15 illustrates the bending of the overlapping portion of the sealing strip;

Fig. 16 is a detail view in section, illustrating the transfer of the blank from the blank cutting mechanism;

Fig. 17 is a detail view in section, illustrating the blank cutting and ejecting mechanism in position to receive the material;

Fig. 18 is a detail view illustrating the relative position of the actuating cams when the parts occupy the position shown in Figs. 1 and 3;

Fig. 19 is an enlarged view of a position of the bending and folding mechanism shown in Figs. 1 and 3;

Fig. 20 is an enlarged side view of the bar and slide of the bending and folding mechanism;

Fig. 21 is an end view of Fig. 20;

Fig. 22 is a plan view of the blank utilized to form the receptacle herein described, the lines of subsequent folding being indicated in dotted lines;

Fig. 23 illustrates the first bending of the blank;

Fig. 24 shows the blank folded upon itself;

Fig. 25 illustrates the bending of the sealed portion of the blank;

Fig. 26 illustrates the folding and sealing of the sealed edges of the blank;

Fig. 27 shows the blank finally assembled in flat form.

A hollow frame 1 substantially rectangular in shape forms the bed or base of the machine and by preference supports at one end the material feeding and blank cutting mechanism. The material feeding is accomplished by carrying a supply of material 2 preferably in roll form upon a shaft 3, in brackets 4 mounted on the frame 1 of the machine. The free end of the paper or material is carried upwardly and over a roller

5 which extends transversely of the machine and is journaled in suitable bearings 6 carried by the frame 1. From this roller 5 the paper projects or travels horizontally between the transverse rollers 7 and 8 rotatably supported by the frame 1 in any suitable manner, the roller 7 being preferably under the pressure of suitable springs 10 to produce a proper tension upon the paper or material.

The paper is automatically and intermittently fed forward between the rolls 7 and 8, to the die or blank cutting mechanism hereafter described, and is accomplished by providing each of the rolls 7 and 8 with a gear 12. The gears 12 mesh and when rotated serve to revolve the rolls in opposite directions. A gear 14 is connected to the roller 8 and meshes with a gear 15 rotatably secured to a stud 16 on the frame 1. This gear

15 is intermittently moved through a partial revolution by means of a dog 17 which engages at times the teeth of the gear and rotates the same. The dog 17 is pivoted to a bell crank 18, movable on the stud 16, and is so constructed that upon a movement in one direction it will engage the teeth of the gear 15 and revolve the same, and when moved in the opposite direction will be disengaged from the teeth of the gear 15, and cease the rotation thereof. The bell-crank 18 and the dog 17 is oscillated by means of the link 20 connected by a pin 21 to a crank plate 22 fast to the continuously revolving drive shaft 23.

The paper or material after passing through the rolls 7 and 8 moves on to the die or blank cutting device where individual blanks are periodically cut from the paper stock to substantially the shape shown in Figs. 7 and 22. The blank cutting device

is of the usual type, one of the cutting members 24 being carried and raised and lowered by posts 25, slidably mounted in the frame 1. The posts 25 at their lower ends are connected by the crosshead 26 carrying a pin

27 to which is connected, intermediate its ends, a lever 28 pivoted at one end as at 30 to a bracket on the main frame 1. The opposite end of the lever 28 carries a roller 31 which engages with and is periodically raised and lowered by the cam 32 fast to the drive shaft 23. A spring 29 connected to the lever 28 and frame 1 acts to hold the roller 31 in contact with the cam 32. The stationary cutting member or anvil 34 of the blank cutting mechanism which is supported on the main frame 1 is transversely bifurcated as at 35 for the reception of the material and is provided with an opening 36 in which the member 24 moves upwardly and downwardly.

The blank 39 after cutting from the stock is deposited upon a carrier or support 37, which in blank receiving position is in vertical alignment with and beneath the die,

where it may readily receive the blank, see Figs. 3, 16 and 17. A positive discharge of the blank from the blank cutting mechanism may be accomplished by providing the movable member 24 with a plunger 38 and operating mechanism as shown in Figs. 16 and 17. The plunger 38 is located within a recess 40 in the bottom of the member 24 when that member is in its uppermost or raised position, see Fig. 17, and is provided with an upwardly projecting stem 41 which slides in the member 24. The member 24 is provided with a recess 42 in which is located a portion of an expansion spring 43, the upper end of which bears against a collar 44 fast to the stem 41. The upper end of the stem 41 is provided with a pin 45 which is engaged by the slotted end 46 of a lever 47 pivoted intermediate its ends as at 48 to a bracket 50 carried by the member 24. The end 51 of the lever 47 is engaged at the proper time by an adjustable screw 52 carried by the post 53 fast to the stationary member 34 on the frame 1. The arrangement of the parts is such that immediately following the cutting of the blank by the downward movement of the member 24, the end 51 of the lever 47 will engage the screw 52 and operate the plunger 38 to discharge the blank upon the support 37, see Fig. 16. Upon the upward movement of the member 24 the spring 43 acts to seat the plunger in the recess 40. Accurate timing of the operation of the plunger may be had by adjusting the screw 52.

After the cutting of the blank the surplus paper may be removed from the machine by rollers 53 and 54 which are located adjacent the forward end of the blank cutting mechanism and extend transversely of the machine. The roller 53 is journaled in suitable bearings supported by the main frame 1 and is rotated by a sprocket wheel 55 connected thereto, which is driven through a chain 56 by a sprocket wheel 57 connected to the roller 8. The roller 54 has each end supported in a movable arm 58 pivoted as at 60 to the main frame 1 and is drawn toward the roller 53 by virtue of the retractile springs 61, connected to the arms 58 and to the frame 1.

The support 37 may be bifurcated or corrugated to permit the blank to lie flat upon the plate and has one of its edges 62 arranged at an angle to the other edges as shown in Figs. 4 and 7. A shoulder 63 may be formed on the support to assist in maintaining the blank in proper position thereon. The blank 39 is received from the die by the supporting plate in the position shown in Fig. 7 and substantially one-half of the blank projecting beyond the edge 62 of the carrier 37 and out of contact with the plate. It will be here noted that it is not necessary that the paper or material be fed

and cut into the desired blanks by mechanism forming a part of this apparatus, although I have shown and described such a mechanism. Suitable blanks may be cut and fed to the support 37 by automatic devices independently of this apparatus or previously cut blanks may be fed by hand to the plate 37.

Following the positioning of the blank 39 upon the support or carrier 37 in the manner just described, the plate is moved forwardly (or to the left in Fig. 4) and a narrow portion 39^a of the blank adjacent the edge 64 of the carrier 37 passes beneath a gluing wheel 65, receiving a coating of adhesive. The support 37 is fast to a slide 66 which is guided and reciprocated horizontally in the main frame 1. To reciprocate the slide one end of a link 67 is attached thereto as at 68 and the other end is pivotally connected as at 70 to one end of a lever 71, the opposite end of which is pivoted as at 72 to the main frame 1. One end of a pitman 73 is pivoted to the lever 71 as at 74 and the other end is provided with a slot 75 in which works the crank pin 76 on the crank plate 77 fast on the drive shaft 23. The slot 75 is elongated as shown in dotted lines in Figure 1 so that when the slide is at the extreme limit of its movement in both directions a period of rest will occur, providing sufficient time for the bending and folding element, hereinafter described, to operate.

Subsequent to the gluing of the portion 39^a the blank is moved further forward by the plate 37 and is transferred to the plate or bed 78 fast to the frame 1. This is accomplished by a finger 80 which is raised slightly above the horizontal plane of the carrier 37 during its forward travel and is lowered immediately in the rear of the blank upon the carrier after the latter has come to rest and over the bed 78. Upon the return movement of the support 37 to its initial position the finger acts to hold the blank and remove it from the carrier whereupon it is deposited on or transferred to the bed 78. The finger 80 is fast to a transverse shaft 81 carried in suitable brackets 82 on the frame 1 and is raised by an arm 83, one end of which is fast to the shaft 81 and the other end of which is connected to a vertical link 84. This link is connected to one end of a lever 85, pivoted intermediate its ends as at 86 to the main frame, and the opposite end of the lever carries a roller 87 which is engaged at the proper time by a cam 88 revolving with the drive shaft 23. The roller 87 is held to contact with the cam 88 and the finger 80 is normally depressed by the retractile spring 89.

The bed 78 is provided with an angularly disposed edge 90 which is parallel with and at times in alignment with the edge 62 of the

support 37. A forming plate 91 is fast to and consequently reciprocates with the slide 66 and is substantially the same shape as the bed 78, and has an angularly disposed edge 92, corresponding with the edge 90 of the bed 78. The longitudinal position of the plate 91 upon the slide 66 is such that when the support is at its rearmost or blank receiving position, the plate 91 will be above and 10 in alignment but out of contact with the bed 78, see Figs. 3 and 8. After the transfer of the blank 39 to the bed 78 the support 37 retreats to its original position to receive a new blank, where it will remain stationary 15 for a short time owing to the slot and pin connection 75-76 which produces a lost motion of the mechanism.

Immediately after the forming plate 91 assumes its position in alignment with the bed 78, the blank is bent upwardly parallel 20 with and along the edges 92 of the plate 91, see Figs. 3, 9 and 12. This is accomplished by a bending and folding element which consists of a bar 93 arranged across the 25 path of travel of the blank and having its major portion closely approaching and parallel to the edge 92 of the forming plate 91. The bar 93 is carried by the slide 59 which works in a guide on the frame 1, and 30 receives a vertical reciprocating motion by means of the roller 69 on the slide working on a cam 79 fast to the drive shaft 23. The shape of the cam 79 is such that at the time the blank is deposited upon the bed 78 the 35 bar 93 is at its lowermost position, a portion of the blank projecting beyond the bed 78 and over the bar 93, see Figs. 8 and 11. A transverse slot 95 is formed in the bar 93, see Figs. 3 and 10, and extends substantially 40 throughout its length. This slot is so located and the shape of the cam 79 is such that when the bar 93 is raised to bend the blank the slot 95 will come to rest for a short interval in alignment with and adjacent the 45 forming plate 91. The depth of the slot is such that the forming plate and the blank will readily pass therethrough as hereafter described.

Following the positioning of the parts as 50 shown in Figs. 3, 9 and 12 the blank is moved forward by the plate 91 through the slot 95 in the bar 93 and is bent substantially upon itself with the plate 91 between the formed halves of the blank, the edge 39^a of 55 the blank contacting with and being sealed to the narrow portion 39^a previously glued by the wheel 65, see Fig. 24.

As the blank upon the forming plate 91 emerges from the slot 95, the sealed edges 60 39^a-39^b and now termed the sealing strip or portion 39^c, is engaged by suitable fingers 96 on the bar 93 which bend the sealed strip 39^c upwardly and at right angles to the remainder of the blank. After engagement 65 with the fingers 96, the strip 39^c receives

a coating of glue or proper adhesive from the wheel 97.

Further forward movement of the forming plate 91 brings the sealed strip 39^c of the blank beneath the beveled edge 98 of an 70 arm 100, carried by the main frame 1, whereupon the sealing strip or portion is folded upon and in contact with the body of the blank and sealed thereto, see Figs. 14 and 26, the strip 39^c having been previously 75 glued by the wheel 97 as before described.

The forming plate 91 with the blank thereon continues its forward movement and comes to rest for a short time at the position shown in Fig. 15. As the forming 80 plate 91 comes to rest, fingers 101 and 102 are lowered behind the blank 39 on the forming plate, and acts to remove the blank from the forming plate, upon its rearward or return movement, and transfer or deposit 85 it upon plate 103 carried on the frame 1 of the machine. The fingers 101 and 102 are fast to a transverse shaft 104 carried in brackets 105 on the frame 1, and are operated by an arm 106 fast to the shaft 104. 90 The arm 106 is connected by a link 107 and arm 108 to the shaft 81 previously described. Since the fingers 80 and 101 and 102 are connected by virtue of the link 107, it is apparent that they will be actuated as a unit 95 or together by the spring 89, cam 88, roller 87, lever 85, link 84, etc., as hereinbefore described.

It will be here noticed, see Fig. 26, that as a result of the folding and sealing of the 100 strip 39^c that a portion 39^d of the strip 39^c projects slightly beyond the apex of the blank. This portion 39^d is bent along the edge 39^e of the blank following its transfer to the plate 103, by a finger 110 on one end 105 of a lever 111 pivoted intermediate its ends as at 112 and supported by the main frame 1. The opposite end of the lever contacts with a shoulder 113 formed on the bar 93, and is operated upon the raising and lowering of the slide 59 and its operating mechanism hereinbefore described. The upward movement of the slide through the shoulder 113 and lever 111 acts to depress the finger 110 and upon the lowering of the slide the finger 114 is raised through the retractile spring 114 which serves to hold the lever 111 in contact with the shoulder 113. One end of the spring 114 may be attached to the lever 111 and the other end may be attached to a 110 reservoir 127 as shown in Fig. 3.

Following the bending of the portion 39^d by the finger 110 the blank is again moved forwardly and presented to the rolls 115 and 116 hereinafter described. To accomplish 125 this a feed roll 120 is adapted to contact at times with the blank and move it forwardly. The feed roll 120 is fast to a shaft 118, rotatably carried in one end of an arm 117, the opposite end of which is supported 130

on a transverse shaft 121. The end of the arm 117 carrying the shaft 118 is provided with a split lug 122 and receives a screw 123 which is adapted to contact with and be raised and lowered by the lever 111 hereinbefore described. The adjustment of the screw 123 should be such that when the finger 110 is raised the arm 117 and roll 120 thereon will be raised sufficiently to admit the proper transfer of the blank from the forming plate 91 to the plate 103 and when the finger is lowered and bends the portion 39^a of the blank as hereinbefore described, the roll 120 will lower into contact with the blank, see Fig. 3. A spring 119 tends to draw the roll 120 into contact with the blank. The roll 120 is rotated by means of a sprocket wheel 124 fast on the shaft 118 which is driven through the chain 125 by a sprocket wheel 126 on the shaft 121.

The blank having been fed forward by the roll 120 during which time the portion 39^a of the blank will have been folded into contact with the blank now passes between the horizontal rolls 115 and 116 and receives a coating of water-proofing material such as hot paraffin, wax, or the like, from the roller 116 which is partially submerged in and rotates in a reservoir 127 for the waterproofing material. The reservoir is provided at its bottom with a chamber 128 into which a heating medium (hot water, steam, heated gases or the like) may be directed to maintain the waterproofing material in a heated and liquid condition. The roll 115 is preferably under suitable spring pressure so that the blank, when passing through the rollers 115 and 116 will not only be fed forwardly but will be pressed and impregnated with the waterproofing material, thereby ensuring a waterproof receptacle. Any improper sealing of the glued portions of the blank will be minimized if not wholly eliminated by the passage of the blank between the rolls.

The rolls 115 and 116 are rotated by means of a sprocket wheel 130, fast on the drive shaft 23, which rotates by means of the chain 131, a toothed wheel 132, connected to one end of the roll 116. The opposite end of the roll 116 is connected to gear 133 which meshes with and drives a gear 134 fast to the shaft 121 on which the upper roller 115 is carried.

The gluing wheels 65 and 97 previously referred to operate in conjunction with and are fed in any suitable manner by the reservoirs 135 and 136, and are rotated by the shafts 137, 138, journaled in bearings on the frame 1. The shafts 137 and 138 are provided at their ends with sprocket wheels 140, 141, which are connected by the chain 142. The shaft 138 is provided with a second sprocket wheel 143 which is driven through the chain 144 by a sprocket wheel 145 fast on one end of a stub shaft 146 journaled in

bearings on the frame 1. A gear 147 fast on the opposite end of the shaft 146 meshes with and is driven by a pinion 148 mounted for rotation with the gear 133 and about the same axis.

After the blank is waterproofed and pressed it may be delivered from the machine in flat form or opened for final shaping of the cup to prevent the adhesion of the contacting sides of the flat blank and for drying. In the latter case after the flat blank passes from between the rollers 115 and 116, it slides down the inclined plate or chute 150 and comes to rest in a vertical position between the horizontal pins 151, beneath a conical former 155, and over the rollers 152, see Figs. 3 and 5. The pins 151 are carried in the upper horizontal bar 153 of a cross-head 154 and the rollers 152 are secured to the upper ends of corresponding levers 156, normally drawn toward one another by the spring 157, and pivotally secured to a lower horizontal bar 158 of the cross-head 154.

Following the delivery of the flat blank to pins 151 the blank is then opened to conical form for shaping and drying. To this end the formed blank is projected onto the former 155, carried by the frame 1, by the cross-head 154 which is slidably mounted upon the vertical standards 160, carried in brackets by the frame 1. The cross-head with the formed blank thereon is raised and lowered by a link 161, one end of which is pivoted as at 162 to the lower horizontal bar 158 of the cross-head 154 and the other end of which is pivotally connected as at 163 to the arm 164 of a bell crank 165. The first part of the upward movement of the cross-head 154 projects the blank 39 onto the former 155 and the continued upward movement of the cross head causes the rollers 152 under the pressure of the spring 157 to travel along the creased edges of the blank and roll or press them upon the face of the former. The last portion of the upward movement of the cross-head carries the rollers 152 just beyond the upper end of the formed blank or cup, (see Fig. 6). The cross-head is then moved downwardly, the rollers 152 stripping the cup from the former 155, whereupon the cup may drop into a receiver 166 carried by the frame 1, see Figs. 3 and 5. The cups may be accumulated as shown and removed collectively, or withdrawn upon each individual delivery to the receiver, or they may after removal from the former 155 be delivered to a conveyor or other suitable mechanism for removing them from the machine.

The bell-crank 165 is pivotally mounted as at 167 to the frame 1 and its arm 168 projects upwardly and carries the roller 170 which contacts with the cam 171 fast on the drive shaft 23. The shape of the cam

70

80

90

95

100

105

115

120

125

130

171 should be such that when a blank has been received by the pins 151 the cross-head will be raised gradually then quickly lowered to remove the blank or cup from the former and maintained in its lower position to await the receipt of the next blank from the rolls 115 and 116. The weight of the cross-head 154 through the link 161 and bell-crank 165 holds the cam roller 170 against the cam 171 and this weight may be partially counterbalanced by the weight 172 carried by the bell-crank to one side of its pivot 167.

15 The shaft 23 is continuously driven and this may be accomplished by the gear 173 fast thereon which meshes with the pinion 174 fast on a shaft 175 driven by an electric motor 176 or any other suitable means.

20 Having thus described the invention what I claim is:—

25 1. The method of forming a receptacle which consists in stamping out a blank of desired form, applying an adhesive to the blank, folding the blank upon itself whereby opposite edges are positioned adjacent each other and sealed, bending the blank adjacent the sealed portion, applying an adhesive to the sealed portion, and then folding and sealing the sealed portion to the blank.

30 2. The method of forming a receptacle which consists in stamping out a blank of desired form, applying an adhesive to the blank, folding the blank upon itself whereby opposite edges are positioned adjacent each other and sealed, bending the blank adjacent the sealed portion, then folding and sealing the sealed portion to the blank, impregnating the folded and sealed blank with a waterproofing agency, expanding the blank, and finally rolling out the creases therein.

35 3. The method of forming a receptacle which consists in punching from a material a blank of desired form, applying an adhesive to the blank, folding the blank upon itself whereby opposite edges are positioned adjacent each other and sealed to form a sealed strip, bending the blank adjacent the sealed strip, applying an adhesive to the sealed strip, folding and sealing the sealed strip to one side of the folded blank, and then folding and sealing a projecting portion of said sealed strip to the opposite side of said folded blank.

40 4. The method of forming a receptacle which consists in folding and sealing a blank to form a collapsed receptacle, impregnating the collapsed receptacle with a waterproofing agency, and then simultaneously expanding the collapsed receptacle and rolling out the creases therein.

45 5. The method of forming receptacles which consists in cutting a blank to the desired form, apply an adhesive to the blank,

folding the blank upon itself whereby opposite edges are located adjacent each other and sealed, bending the blank adjacent the sealed portion, applying an adhesive to the sealed portion, folding and sealing the sealed portion to the blank, and impregnating the folded blank with a water proofing agency.

6. The method of forming receptacles which consists in applying an adhesive to an edge of a blank cut to desired form, folding the blank upon itself whereby opposite edges are located adjacent each other and sealed, bending the blank adjacent to and parallel with the sealed portion, applying an adhesive to the sealed portion, folding and sealing the sealed portion to the blank, impregnating the folded blank with a waterproofing agency and expanding the blank to final form.

7. The method of forming a waterproof receptacle consisting in folding, sealing and impregnating a blank to form a collapsed flattened receptacle, and then rolling out the creases therein.

8. The method of forming conical receptacles which consists in forming a suitable blank in flat form and then expanding and rolling the blank to conical form.

9. The combination with means for feeding material and cutting a blank therefrom, devices for folding and sealing portions of the blank to form a collapsed cup, means for transferring the collapsed cup from one of said devices to another, a stationary expanding member, means for forcing the collapsed cup on said expanding member to expand the cup, and rollers for rolling out the creases in said cup.

10. The combination with means for feeding material and cutting a blank therefrom, means for folding and sealing a blank to form a collapsed cup, means for impregnating the collapsed cup, and mechanisms for simultaneously expanding the collapsed cup and rolling out the creases therein.

11. In apparatus of the character described the combination of means for presenting a supply of material, means for cutting blanks from the material when presented, mechanism for folding and sealing portions of said blank maintaining the blank meanwhile in flat form, means for waterproofing said formed blank while flat, conical means for expanding the formed blank, and rollers for pressing the formed blank to final expanded form on said conical means.

12. In an apparatus of the character described, the combination of means for cutting a blank, means for receiving the cut blank, a spring controlled plunger for effecting a positive discharge of the blank from the cutting means to the receiving means, and adjustable means for actuating said plunger.

13. In a machine of the character described, the combination of means for cutting a blank, means for bending and folding the blank, a carrier for the blank, means for operating the carrier back and forth between the cutting means and the bending and folding means to feed the folded blank through the machine, a stationary former, a receiver for supporting the folded blank, means for raising the receiver to force the folded blank onto the former, and spring controlled roller mechanisms on the receiver adapted to be elevated therewith and be separated by the former whereby the creases are rolled out of the expanded blank. 10
14. In an apparatus of the character described, the combination with means for cutting a blank, and means for bending and folding the blank, a carrier for the blank operable back and forth between the blank cutting means and the bending and folding means, means independent of the carrier for removing the blank therefrom, cam operated mechanisms for actuating the removing means, means for impregnating and pressing the folded blank, an expanding form, and means for elevating the impregnated folded blank and pushing the same on said form to open the folded blank. 20
15. In a device for forming receptacles, the combination of a stationary frame, a blank cutting device supported thereon, a carrier movable in the frame in a horizontal plane for transferring the blanks, an element movable in a plane at an angle to the path of travel of the carrier for bending the blank subsequent to its transfer, a slideable member for moving said element, a roller thereon, and a cam mechanism engaged with said roller for operating the slideable member. 30
16. In a device for forming receptacles, the combination of means for advancing a supply of material, means for cutting blanks therefrom, a bed, a carrier for transferring the blank from the blank cutting device to a position over the bed, means for applying adhesive to a portion of the blank during its translatory movement, means for transferring the blank from the carrier to the bed, a movable forming plate having a position of rest over the bed, and blank thereon, means for bending the blank upon the forming plate and operative in conjunction therewith, to fold and seal the blank thereon, means for moving the forming plate out of cooperative relation with said bending means, a device for further bending the portions of the blank upon the forming plate, means for removing the blank from the forming plate, means adapted to apply the waterproofing agency to the blank when presented, means for presenting the folded blank to the waterproofing means, and means for opening the blank to final form subsequent to its contact with the waterproofing means. 40
17. In a device for forming receptacles, the combination of means for advancing a supply of material, means for cutting blanks therefrom, a bed, a carrier for transferring the blank from the blank cutting device to a position over the bed, means for applying adhesive to a portion of the blank during its translatory movement, means for transferring the blank from the carrier to the bed, a movable forming plate having a position of rest over the bed and blank thereon, means for bending the blank upon the forming plate and operative in conjunction therewith, to fold and seal the blank thereon, means for moving the forming plate out of cooperative relation with said bending means, a device for further bending the portions of the blank upon the forming plate, means for removing the blank from the forming plate, means adapted to apply the waterproofing agency to the blank when presented, means for presenting the folded blank to the waterproofing means, a stationary expanding member, a slideable support, members thereon for receiving the folded impregnated form, arms pivoted on said slideable support, rollers thereon, a spring connecting said arms, and cam operated means for operating said slideable support to force the folded blank over said expanding member as the rollers roll out the creases therein. 50
18. The method of forming a receptacle consisting of first producing a collapsed receptacle, and then simultaneously expanding the same and rolling out the creases therein. 60
19. The method of forming a receptacle consisting of first producing a collapsed creased receptacle, and then forcing the same over a stationary former into expanded form. 70
20. The method of forming a receptacle consisting of first producing a collapsed creased receptacle, and then forcing the same on a stationary former and removing the creases from the expanded receptacle. 80
21. The method of forming a receptacle consisting of producing a collapsed creased receptacle, forcing the collapsed receptacle on an expanding means, and then applying rollers to the expanded receptacle to roll out the creases and cause ejection of the receptacle from the expanding means. 90
22. The combination with means for feeding material and cutting a blank therefrom, means for folding and sealing a blank to form a collapsed cup, means for impregnating the collapsed cup, a former, means for pushing the collapsed cup onto the former to expand the cup, and roller mechanisms carried by the pushing means adapted to first roll out the creases in the expanded cup and then strip said cup from the former. 100
23. The combination with a mechanism for producing a collapsed flat cup, of a 110

former, and movable means for receiving the collapsed cup and forcing the same over said former to expand the cup.

24. The combination with a mechanism for producing a collapsed flat cup, of a former, movable means for receiving the collapsed cup and forcing the same over said former to expand the cup, and roller mechanisms carried by the movable means adapted to be separated by the former to roll out the creases in the expanded cup while on the former.

25. The combination with a mechanism for producing a collapsed cup, of a former, movable means for receiving the collapsed cup and pushing the same over said former to expand the cup, and means on said movable means adapted to first remove the creases from the expanded cup and then strip said cup from the former.

26. The combination with a former, of means for forcing a collapsed cup onto the former to expand the cup, and mechanisms on said means for removing the creases from the expanded cup and then stripping the cup from the former.

27. The combination with a former, of

means for holding a collapsed cup and pushing the same onto the former to expand the cup, spring connected arms pivoted on said means, and rollers on said arms, said arms adapted to be separated by said former to permit the rollers to first roll out the creases in said expanded cup and then strip said cup from the former.

28. The combination with a collapsed cup forming machine, of a cup expanding device, and a mechanism operable by the machine for receiving a collapsed cup from the machine, pushing the same on the expanding device to be expanded, and then stripping the expanded cup from the expanding device.

29. In a cup forming machine the combination with a collapsed cup expanding means, of a mechanism for automatically pushing collapsed cups thereon and then pulling the expanded cups therefrom.

In testimony whereof I affix my signature in the presence of two witnesses.

CESARE BARBIERI.
